UNITED STATES PATENT OFFICE.

SAMUEL HERBERT, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,144,762.

Specification of Letters Patent. Patented June 29, 1915.

Application filed March 11, 1911. Serial No. 613,771.

To all whom it may concern:

Be it known that I, SAMUEL HERBERT, a citizen of the United States of America, residing at Detroit, in the county of Wayne and State of Michigan, have invented certain new and useful Improvements in Car-Roofs, of which the following is a specification, reference being had therein to the accompanying drawings.

10 The invention relates to car roofs and more particularly to that type in which the spaces between the carlines are covered by metallic roofing sheets, forming not only a water-proofing means—but also the load-sustaining members. With such constructions it is essential to securely fasten the plates at the eaves, and it is usual to accomplish this by bolts, nails or clips engaging the depending flanges at the eaves and 15 passing through the fascia sheathing and into or through the side plate of the car. Such a construction forms an effective securing means, but it has been found in use that rain water will occasionally pass 20 through the aperture for the bolt or nail and find access to the interior of the car. It is not necessary that the water should pass through the plate, but merely to pass through the fascia and sheathing to the line 25 of the inner face of the siding, where it will drop down and enter the interior of the car.

It is the object of the present invention to avoid this defect by obtaining a fastening means for the sheets not penetrating to the interior of the case, and at the same time to firmly anchor the fastening means to the side plate, and to this end the invention consists in the construction as herein- 30 after set forth.

In the drawings,—Figure 1 is a plan view of a portion of the car to which my improvements are applied; Fig. 2 is a side elevation thereof; and Fig. 3 is a section on line α — α of Fig. 1.

A is the side plate, B the siding and C is the fascia overlapping the upper ends of the siding.

D is a metallic roofing plate having a 50 downwardly extending flange E overlapping the fascia, and F is the carline cap which is provided with a similar downwardly projecting eaves flange F'.

The fascia C is preferably secured to the side plate by the insertion of a filler strip 55 G between its inner face and the outer face of the plate, said filler block being slightly greater in thickness than the siding of the car to provide a clearance between the overlapping portion of the fascia and said siding. Thus the fascia is completely outside of the car, and any water penetrating to its inner face will drop through the clearance space outside of the siding.

The direct securing means for the roofing 65 sheets is attached to the fascia without penetrating to the interior of the car, and as shown, a series of bolts H are arranged to pass through the fascia with their heads engaging recesses H' in its inner face. These 70 bolts extend outward and engage the depending eaves flanges E of the roofing sheets which are secured thereto by nuts H². The flanges E may if desired, be spaced from the fascia by thimbles H³, but when the ends 75 are secured the flange is firmly anchored from disengagement. Inasmuch as the bolts H do not pass farther than the inner face of the fascia, which is outside of the line of the siding, it is evident that any water 80 passing through the bolt aperture cannot penetrate into the car but will merely drop through the clearance space between the fascia and siding. It is however, necessary to firmly anchor the fascia to the plate, 85 which is preferably accomplished by a second series of bolts I which pass through the aligned apertures in the fascia, filler strip G and plate. These securing bolts I are effectively weather guarded by the depending flanges E which are imperforate in the portions covering said bolts, and thus no opportunity is afforded for the penetration 90 of moisture to the interior of the car.

To secure the metallic carlines in position 95 without forming any bolt holes or openings to the outside of the car, they may be secured by brackets K engaging the top and inner side of the plate. These brackets are secured by vertical bolts M passing through the plate and which are protected by the carline caps F, and are also secured by transversely extending bolts N which pass through the plate but do not puncture either the filler or the fascia. The heads of these 100 bolts engage recesses in the outer face of 105

the plate and when secured in position are effectively weather guarded by the filler strip G.

What I claim as my invention is:

- 5 1. In a car, the combination with the plate and siding, of a fascia having its outer face outside the plane of the outer face of said siding, a filler strip between said fascia and plate, a roofing sheet having a depending flange, securing means for said flange passing through said flange and fascia only, and weather guarded securing means for said fascia passing therethrough and through said filler strip into the plate.
- 10 15 2. In a car, the combination with the plate, siding and fascia, of a filler strip of greater thickness than the siding positioned

between the fascia and plate with its outer face outside the line of the outer face of the siding, an inwardly extending bolt passing through alined apertures in said fascia, filler strip and plate, a roofing sheet having a downturned flange at the eaves weather-guarding said bolt, and an outwardly extending bolt out of alinement with the first mentioned bolt passing through alined apertures in said flange and the fascia only.

In testimony whereof I affix my signature in presence of two witnesses.

SAMUEL HERBERT.
